ATTORNEY.

UNITED STATES PATENT OFFICE.

JAMES T. SARGENT, OF CLEVELAND, OHIO.

WASH-BOARD.

SPECIFICATION forming part of Letters Patent No. 327,601, dated October 6, 1885.

Application filed April 1, 1885. Serial No. 160,873. (No model.)

To all whom it may concern:

Be it known that I, JAMES T. SARGENT, a citizen of the United States, residing at Cleveland, in the county of Cuyahoga and State of Ohio, have invented or discovered certain new and useful Improvements in Wash-Boards, of which improvements the following is a specification.

In the accompanying drawings, which make part of this specification, Figure 1 is a front elevation of a wash-board embodying my improved form of soap-box. Fig. 2 is a longitudinal section of the same. Figs. 3 and 4 are views similar to Figs. 1 and 2, showing a modified form of soap-box.

My invention relates to an improvement in what are termed "double-faced" wash-boards, the object of said improvement being to provide a soap-box on each side of the board of a capacity equal to or greater than the soap-boxes formed on single-faced boards; and to this end my invention consists in the construction and combination of parts, all as more fully hereinafter described and claimed.

The wash-board A is of the usual form and construction, consisting of the rubbing-faces 2, of any known and suitable construction, and a supporting-back inserted between the rubbing-faces, and suitably secured to the side bars, 3. These side bars are extended, as usual, above the ends of the rubbing-faces, and are connected at their upper ends by head bar or piece 5. As shown, the upper ends of the rubbing-plates 2 are bent over the upper end of supporting-back, and are held in position by the cross-bar 6, bearing against the turned-over ends of the rubbing-plates, said bar being secured at its ends to the side bars, 3. To the side bars, 3, midway between the head-piece 5 and the cross-bar 6, is pivoted the brand-board 7, forming in connection with the side bars and head and cross-bars a receptacle for the soap. Although it is within the scope of the invention herein to connect the brand-board directly to the side bars by the pivot-pins 8, it is preferred to secure the brand-board to side pieces, 9, said side pieces being of a width somewhat greater than half the width of the side bars, and through these side pieces are passed the pivot-pins 8, the distance between the holes for these pins in the side pieces and the brand-board being

nearly equal to half the width of the side bars, 3. By this construction the brand-board when reversed from one side of the wash-board to the other will be approximately in line with the edges of the side bars, thus forming on either side a soap-box of a depth approximately equal to the width of the side bars, 3. Along the under side of the head-piece 5 is formed a rib or projection, 10, against which the edges of the brand-board strike when turned from one side to the other, said rib or projection being so constructed and proportioned that when one edge of the brand-board is in contact therewith the opposite edge will be held a short distance away from the cross-bar 6, thereby forming a drip-opening for the escape of water on that side of the wash-board not in use. In some cases it is desirable that the brand-board should be capable of turning a little more than one hundred and eighty degrees through the side bars, 3, and assume a position when turned parallel with the rubbing-faces, but in a different plane, in which case the side pieces, 9, are made a little shorter than the distance between the head-piece 5 and cross-bar 6, and the brand-board is made sufficiently wide to project beyond the side pieces, 9, on each side far enough to abut against the rib or projection 10, as above stated. In such a construction the pivot-pin is located midway of the side pieces, 9, and of that part of the side bars, 3, included between the head-piece and cross-bar 6, as clearly shown in Fig. 4, the brand-board extending to or nearly to the upper edge of the cross-bar 6; but in some cases it is desirable that the brand-board should extend beyond or lap over the cross-piece 6, in which case both the brand-board and side pieces are made of a width greater than the distance between the head-piece 5 and cross-bar 6, the side pieces being made of a length equal to the width of the brand-board, and the pivot-pin, while passing through the side pieces midway of their length, projects into the side bars, 3, at a point distant from the central point between the head-piece and cross-bar equal to the excess of width of the brand-board over the width of the opening in which it is located, so that the upper edge of the brand-board will extend to, but not beyond, the rib on the under side of the head-piece, while its lower edge

will lap over or project beyond the cross-bar 5, as clearly shown in Fig. 2, thus forming an apron or guide to prevent the water from splashing through the opening between the brand-board and cross-bar, and causing it to flow down into the tub behind the wash-board.

It will be observed that in this construction the brand-board, when turned to place on either side of the wash-board, extends diagonally across the opening between the head-piece and cross-bar; hence, in order to obtain the desired depth of soap-box, the holding face of the brand-board is made concave, as shown, which construction will give the desired depth in that part of the box in which the soap is retained.

To the head-piece is attached a suitable catch adapted to hold the upper edge of the brand-board in place, and to prevent its accidental turning—as, for example, a double hook, 11, journaled in the head-piece, and constructed to catch over the upper edge of the brand-board on either side, may be employed.

5 I claim herein as my invention—

1. In a wash-board, a brand-board pivoted to the side bars and constructed to be rotated in the opening in the head of the wash-board, substantially as and for the purpose set forth.
2. In a wash-board, a brand-board pivoted to the side bars and constructed to be rotated in the opening in the head of the wash-board, in combination with a suitable stop whereby

to prevent too great a length of rotary motion, substantially as set forth.

3. In a wash-board, a brand-board pivoted to the side bars and constructed to be rotated in the opening in the head of the wash-board, in combination with a suitable stop whereby to prevent too great a length of rotary motion, and a catch to hold it in place when rotated to position, substantially as set forth.

4. In combination with a wash-board frame, a pivoted rotary brand-board, made with its pivotal points outside the plane of the brand-board itself, substantially as set forth.

5. In a wash-board, a brand-board provided with side pieces, said side pieces being pivotally connected to the side bars, said brand-board and side pieces being constructed to rotate in the opening in the head of the wash-board, whereby a soap-box may be formed on either side of the wash-board, substantially as set forth.

6. In a wash-board, a brand-board pivoted to the side bars at a point below the center of the opening between the cross-bar 6 and head-piece 5, said brand-board being constructed to oscillate in said opening, substantially as set forth.

In testimony whereof I have hereunto set my hand.

JAMES T. SARGENT.
